[57] CLAIM

The ornamental design for a snow scoop or similar article, as shown and described.

DESCRIPTION

FIG. 1 is a perspective view of a snow scoop or similar article showing my new design;

FIG. 2 is a front elevational view thereof;

FIG. 3 is a rear elevational view thereof;

FIG. 4 is a bottom plan view thereof;

FIG. 5 is a top plan view thereof; and,

FIG. 6 is a left side elevational view thereof with the right side being a mirror image thereof.

The broken line showing a snow scoop handle in FIG. 1 is for illustrative purposes only and forms no part of the claimed design.
